UNITED STATES PATENT OFFICE.

EDWIN PROBST, OF CINCINNATI, OHIO.

ENGRAVER'S TOOL.

985,934.

Specification of Letters Patent. Patented Mar. 7, 1911.

Application filed April 30, 1908. Serial No. 430,121.

To all whom it may concern:

Be it known that I, EDWIN PROBST, a citizen of the United States, residing at No. 311 Northern avenue, Cincinnati, in the 5 county of Hamilton, State of Ohio, have invented a new and useful Engraver's Tool, of which the following is a specification.

My invention relates to the improvement of engraver's tools for cutting or engraving 10 purposes in which the blade and handle are separate pieces.

Figure 1 of the drawing is a representation of the engraver's tool entire. Fig. 2 is a sectional view of the same.

15 This invention has relation to engraver's tools, and it consists of a tool having a hollow handle in which by means of a sliding steel bar, two set screws, and a knife blade, fitted with a shouldered shaft, the said 20 knife blade may be adjusted and fastened in such a manner that the point of said knife will at all times be at uniform distance from the handle regardless of decrease in the length of said knife caused by wear, 25 thus affording the operator the greater power that a tool of uniform length affords.

In the annexed drawings "A" designates the wooden handle which is hollow.

"B" designates a brass tube fastened onto 30 the handle.

B² is a sliding steel bar which holds the knife.

D is the shank of the blade which fits into

the sliding steel bar being held therein by the set screw F. The end of the shank has 35 a shoulder G which abuts against a pin C passing through the sliding steel bar.

E is a set screw by means of which the sliding steel bar is held rigid in the handle and which allows the point of the knife to 40 be extended or drawn back.

A—B²—D—E—F. and C. are the handle and its working parts which is sought to be patented. The knife blade being the one now commonly in use except for 45 the shaft with the shouldered end which is simply to allow of its adjustment securely into the sliding steel bar.

I claim:

The combination in an engraver's tool of 50 a hollow recessed handle containing a brass tube, a sliding steel bar having a shouldered end, a blade having a shouldered end, a steel bar pin passing through said sliding steel bar, and two set screws one for the 55 purpose of fastening the blade into the sliding steel bar against the shouldered end of the shaft and another set screw for the purpose of holding rigid in the handle this combination of the sliding steel bar and 60 knife.

EDWIN PROBST.
